ANTON STRAKA, OF CHICAGO, ILLINOIS

GRAPPLING HOOK

Application filed December 9, 1930. Serial No. 501,133.

This invention relates to improvements in grappling hooks, and is particularly adapted for raising or lifting broken well tubing from a well, but it is to be understood that it may be used for other purposes, and the invention comprises a pair of crossed levers being provided with substantially parallel portions at one end which form the jaws or gripping members, while the opposite ends of each of the cross levers is provided with a ring or looped portion for receiving connecting and lifting links. The invention also comprises means for locking the parallel jaws against collapsing while being lowered into the well and means is also provided for preventing expansion or locking the jaws in position upon a piece of well tubing after the first mentioned means has been automatically released. Further, the invention comprises a novel construction locking ring movable upon the gripping jaws of the crossed levers and limited against upward movement by means of stops carried by the parallel portions of the crossed levers.

The primary object of this invention, is to provide a device of the above mentioned character which is simple in operation and construction and which may be manufactured at a minimum cost.

A further object of this invention, is to provide a device of the above mentioned character whereby the vertical pull on the connecting links will cause the gripping jaws to be forced upwardly in the direction of the object being fished for.

Heretofore, it has been common practice to provide crossed levers having one of their ends provided with gripping members and the opposite ends connected together by links or levers suitably connected to a pole or lifting line. In the devices of the prior structures, means was not provided for preventing the expansion of the gripping members, while being lowered into position and upon the broken well tubing or other objects in the well, whereupon the gripping jaws frequently would engage the side walls of the well and become lodged against displacement, making it difficult in operation and performance.

The above objections and disadvantages are overcome by providing a device in which means is provided for locking the jaws against expansion while being lowered into the well or to the casing whereby the jaws will not expand and engage the walls, resulting in jamming and sticking.

Other objects and advantages of the invention will become apparent during the course of the following description, forming a part of this specification, and in which,

Figure 1 is a vertical elevation of the invention showing the manner in which the expansion lock is slidably mounted on the parallel jaw sections and also showing the position of the lock for holding the jaws in a set position;

Figure 2 is a side elevation illustrating the crossed levers and the construction of the locking ring as associated with the parallel portions or gripping jaws of the parallel levers;

Figure 3 is a vertical front elevation of the invention showing the same as applied in operation, and illustrating the jaws presented to a broken well tube or one which has become disconnected from the line;

Figure 4 is a transverse cross-sectional view taken on line 4-4 of Figure 1, looking in the direction of the arrows, illustrating the latch or lock engageable by the well tubing and operable thereby for allowing the jaws to grip the object and to be moved together;

Figure 5 is a transverse cross-sectional view taken on line 5-5 of Figure 1, looking in the direction of the arrows showing the contour of the locking ring and the manner in which it is positioned on the parallel portion of the cross-levers whereby the same may pass over the tubing when in its downward or locking position;

Figure 6 is a cross sectional view taken on line 6-6 of Figure 1;

Figure 7 is a side elevational view further illustrating the general contour of one of the crossed levers; and

Figure 8 is another side elevational view of the crossed lever shown in Figure 7.

In the drawings, and wherein for the purpose of illustrating the invention and where-

in like reference characters will be employed to designate like parts throughout the same, the reference characters 5 and 6 will generally be employed to designate a pair of crossed levers having complementary offset portions 7 and 8 suitably flattened for allowing the passage of a pivot pin or rivet 9. Each of the crossed levers 5 and 6 are provided with extensions 10 and 11 upon the outer ends of which are formed eyelets 12 having openings 13 for the passage of a pair of rings 14. Each of the rings 14 are connected by a main ring 15 through which may be passed a rope or wire cable suitably looped and fastened for lowering and raising the crossed levers 5 and 6 in and out of a well or other restricted opening.

The lower ends of the crossed levers 5 and 6 are provided with angular portions 16 and 17 terminating in spaced parallel portions 18 and 19. Each of the free ends of the parallel portions 18 and 19 are provided with gripping members 20 which may engage an object and frictionally hold the object against displacement.

In Figure 3, is illustrated the manner in which the crossed levers 5 and 6 are adapted to be lowered into a well and positioned relative to a broken pipe or one which has become disconnected from the line and the jaws are shown presented to the side portions of the pipe A ready for being lifted or hoisted out of the well. Means is provided for preventing the jaws 18 and 19 from collapsing while being lowered into the well and the means includes a latch 21 having one end thereof bifurcated as at 22 to provide furcations 23. The furcations 23 are adapted to straddle the parallel jaw 18 and be held in place in a pivotal fashion by means of a pivot pin 24 passing through suitable openings 25 in the furcations 23. It will be noted that the latch 21 is peculiarly shaped and is arcuately curved downwardly toward the ends of the jaws 18 and 19, preferably in the direction of the gripping jaws 20. The free end of the latch 21 is notched as at 26 in order that the same may be guided upon the straight parallel jaw 19 whereupon it is limited against downward movement by a detent 27 suitably secured to the jaw 19 as clearly illustrated in Figure 1. It is to be understood, that when the crossed levers 5 and 6 are positioned in the well and lowered in close proximity to the broken tube or well casing that the latch 21 is engaged by the top of the pipe which moves the latch 21 upwardly relative to the jaws 18 and 19 and thereby allows the collapse or inward movement toward the pipe or casing of the jaws.

After the jaws have been thus moved inwardly, and the latch 21 released, the lower portions of the jaws 18 and 19 are closer together than the top portions thereof which allows the downward movement of a retain-

ing or locking ring 28 which is slidably mounted upon the parallel jaw portions 18 and 19 and which is limited against upward movement by suitable stops 29 anchored in the parallel jaws 18 and 19 in close proximity to the angular portions 16 and 17. The locking ring 28 is provided with an offset portion 30 forming an inner depression 31 for reception of one of the parallel jaw portions 18 or 19. 70 75

It is to be understood, that as soon as the latch 21 is released the lower portions of the jaws 18 and 19 are closer together whereupon the locking ring 28 is allowed to fall or move downwardly upon the straight portions 18 and 19 of the jaws and thereby lock the jaws into engagement with the object being fished from the well. Normally, the lower portion of the parallel jaw portions 18 and 19 are extended a greater distance than the upper portions and are held in this position by means of the latch 21, whereby the downward movement of the lock 28 is prevented. 80 85

For a consideration of the operation of the invention, attention is directed particularly to Figures 1 and 3, wherein is shown the assembled device and it is first to be noted that as illustrated in Figure 1, the crossed levers 5 and 6 are in position to be lowered into the well as they are held in expanded position by means of the latch 21. After the crossed levers 5 and 6 are lowered into contact with the well tubing, the latch 21 is engaged thereby and is moved upwardly thereby allowing the weight of the crossed levers on the suspending means such as a rope or cable to cause the levers and jaws 18 and 19 to be moved together, whereupon the jaw faces 20 engage the pipe or line which are held in close contact therewith by means of the locking ring 28 which moves downwardly after the jaws 18 and 19 have been released by the latch 21. It will be noted that the locking ring 28 is particularly constructed in such a manner that the same will pass over the pipe or well tubing when the pipe passes between the jaws 18 and 19 and moves the latch 21. In this manner, the locking ring 28 is moved downwardly by gravity and engages the lower portions of the parallel jaw portions 18 and 19, thus holding the jaw faces 20 in close relation to the pipe or well tubing and against slippage. 90 95 100 105 110 115

It is to be understood, that the form of the invention herewith shown and described is to be taken as a preferred embodiment of the same and that various changes in the shape, size and arrangement of parts may be resorted to without departing from the spirit and scope of the invention as claimed. 120 125

Having thus described the invention, what is claimed is:—

1. A well fishing tool of the character described, comprising a pair of crossed pivoted levers, connecting links connecting the upper 120

ends of the crossed levers, parallel jaw portions formed on the opposite ends of the crossed levers, friction gripping members secured to the free ends of the spaced parallel portions, means pivoted to one of the spaced parallel portions, having its free end engaging the opposite parallel portion, a detent carried by the spaced parallel portion in close relation to the free end of the first named 10 means for limiting the downward movement thereof and a locking ring slidably mounted upon the spaced parallel portions.

2. A well fishing tool of the character described, comprising a pair of crossed levers, 15 links and suspending means connecting the upper ends of the crossed levers, each of the lower ends of the crossed levers being provided with a spaced parallel portion, a latch having one of its ends pivoted to one of the 20 spaced parallel portions and its free end engaging the opposite spaced parallel portion of the crossed levers, means carried by one of the spaced parallel portions of the levers for limiting the downward movement of the 25 latch, and a locking ring slidably mounted upon the spaced parallel portions of the levers for holding the jaws in a locked position after the release of the latch.

3. A well fishing tool of the character described, comprising a pair of crossed levers, 30 said levers being pivotally connected intermediate their ends for pivotal movement, links connecting the upper ends of the crossed levers, spaced parallel portions formed on the 35 opposite ends of the crossed levers, jaw faces secured to the free ends of the spaced parallel portions, a latch having one of its ends pivoted to one of the spaced parallel portions and its opposite end engaging the opposite spaced 40 parallel portion, means formed on the opposite spaced parallel portion for limiting the downward movement of the free end of the latch, whereby the spaced parallel portions will normally be held in substantially parallel 45 relation, a lock ring slidably positioned on the spaced parallel portions of the crossed levers, means on the upper portion of each of the spaced parallel portions of the crossed levers for limiting the upward movement of the 50 locking ring, and means for suspending the crossed levers in a well whereupon the latch may engage the object for releasing the spaced parallel portions and the locking ring will be caused to move downwardly upon the 55 release of the latch for holding the jaws in engagement with the object being grappled.

4. A fishing tool of the character described, 60 comprising a pair of crossed parallel levers, connected links connecting the upper end of the crossed parallel levers whereby a suspension means may be passed through one of the links for lowering the crossed levers into a well, means associated with the opposite ends of the crossed levers for engaging and frictionally holding an object, and a locking ring 65

slidably mounted on the crossed levers for holding the jaws in close relation and locked position relative to the object being grappled.

In testimony whereof I affix my signature.
